UNITED STATES PATENT OFFICE.

ALPHONSO S. CAMPBELL, OF WEST MEDFORD, MASSACHUSETTS, ASSIGNOR TO A. S. CAMPBELL COMPANY, OF BOSTON, MASSACHUSETTS, A CORPORATION OF MASSACHUSETTS.

WINDOW FRAME.

Application filed August 21, 1920. Serial No. 405,088.

To all whom it may concern:

Be it known that I, ALPHONSO S. CAMPBELL, a citizen of the United States, and resident of West Medford, county of Middlesex, State of Massachusetts, have invented an Improvement in Window Frames, of which the following description, in connection with the accompanying drawings, is a specification, like characters on the drawings 10 representing like parts.

This invention pertains to improvements in window frames.

It is among the objects of the invention to provide for the simple, effective and inexpensive attachment of curtain windows to curtains and the like.

In the drawings:—

Figure 1 is an elevation of a curtain carrying a curtain window;

20 Fig. 2 is a section on the line 2—2 of Fig. 1;

Figs. 3, 4, 5, 6 and 7 are diagrammatic views, showing cross-sections of the preferred form of curtain window frame at 25 various stages of the manufacture thereof;

Fig. 8 illustrates diagrammatically a preferred apparatus for finally clenching the glass, frame and curtain in assembled relationship; and

30 Figs. 9, 10, 11, 12, 13 and 14 are views similar to those shown in Figs. 3 through 7 as applied to a modification.

Referring to the drawings and to the preferred form of my invention selected for

35 illustrative purposes, I have shown a curtain window including a glass 15 secured to fabric 16 by a frame 17. The frame 17 may be formed from a flat piece of metal by first pressing up the flange 18 (Fig. 3), then

40 pressing up the flanges 19, 20 (Fig. 4), and then spinning or pressing outwardly the flange 20 (as shown in Fig. 5). It will be

understood that the sections shown in Figs. 3, 4, 5 and 6 are through portions only of 45 the frame. The frame when formed as shown in Fig. 5, may be laid upon the curtain fabric and the curtain fabric slashed and cut to permit turning back of the edges thereof over portions of the frame, as illus-

50 trated in Fig. 6. The glass 15 may then be inserted, as shown in Fig. 7, and the upstanding flange 18 spun or pressed inwardly to overlie the glass and to hold the glass

fabric and frame in determined assembled 55 relationship.

Figs. 9 through 13 illustrate a construction very similar to that shown in Figs. 3 through 7, except that the flange 19 is bent in the opposite direction from that shown in the preceding figures, this conveniently 60 providing a cushion for the edge of the glass where inserted with its beveled surface facing in the opposite direction from that shown in Fig. 7.

In Fig. 14 I have illustrated the use of a 65 plain as distinguished from a beveled glass.

The preferred forms of frame illustrated are particularly advantageous in that they include a single metallic portion having flanges exerting restraining pressure on both 70 faces of the glass, such flanges preferably overlying both faces of the glass. The fabric cushions the glass on at least one side and the frame is only visible from one side 75 of the curtain, because the frame is entirely overlain by the fabric on one side. The frame and glass preferably, as shown, lie entirely on one side of the general plane of the fabric.

While I have shown and described a preferred form of my invention, it will be understood that changes involving omission, substitution, alteration and reversal of parts, and even changes in the mode of operation, may be made without departing from the 85 scope of my invention, which is best defined in the following claims.

Claims.

1. A curtain window installation comprising, in combination, a glass, the fabric, and a metallic frame, said metallic frame including a single metallic portion having generally continuous flanges exerting retaining pressure on both faces of said glass, said fabric pressed between said metallic portion 90 and said glass and cushioning said glass.

2. A curtain window installation comprising, in combination, a glass, the fabric, and a securing frame, said fabric overlying one side of said frame and extending between 95 said side of the frame and the glass, the other side of said frame unitary with the first-mentioned side of said frame, flanged inwardly to press the glass against the adjacent fabric.

3. A curtain window installation comprising

100

105

ing, in combination, a glass, the fabric and a frame, said fabric apertured for the window and having turned back portions thereof between the frame and glass to provide a cushion for the glass at one side, the frame presenting a single piece of metal supporting the glass at said side and also providing

a curved-over portion engaging the face of the glass on the opposite side of the glass from said turned back portions of the fabric. ¹⁰

In testimony whereof I have signed my name to this specification.

ALPHONSO S. CAMPBELL.
